B. SETTERGREN.

MARINE VESSEL.

APPLICATION FILED DEC. 2, 1907. RENEWED SEPT. 10, 1909.

955,703.

Patented Apr. 19, 1910.

UNITED STATES PATENT OFFICE.

BERNHARD SETTERGREN, OF CHICAGO, ILLINOIS, ASSIGNOR TO JOHN GUBBINS, OF CHICAGO, ILLINOIS.

MARINE VESSEL.

955,703.

Specification of Letters Patent.

Patented Apr. 19, 1910.

Application filed December 2, 1907, Serial No. 404,731. Renewed September 10, 1909. Serial No. 517,110.

To all whom it may concern:

Be it known that I, BERNHARD SETTERGREN, a citizen of the United States, and a resident of Chicago, in the county of Cook and State of Illinois, have invented certain new and useful Improvements in Marine Vessels, of which the following is a full, clear, and exact description.

My invention relates to improvements in marine navigation and its object is to provide suitable means for assisting the propulsion of boats through the water whereby the friction caused by the hull of the boat as it cuts rapidly through the water is considerably reduced and the boat is permitted to ride more smoothly and rapidly than has heretofore been possible with vessels of ordinary construction.

In carrying out my invention it is expedient that the same be so arranged that a current of air will be forced from below the hull of the vessel in such manner that the greater portion of said hull will ride upon the bubbles caused by said air-current, but which will become displaced from under the hull at a point sufficiently forward of the propelling means so as not to interfere with the force thereof in the water or present any back pressure. This I accomplish by the means hereinafter fully described and as particularly pointed out in the claims.

In the drawings:—Figure 1 is a broadside view of a launch or other vessel showing my invention applied thereto. Fig. 2 is a deck view thereof. Fig. 3 is an amidship section drawn to a larger scale. Fig. 4 is a horizontal view of a portion of the bow taken below the water-line.

Referring to the drawings 1 represents the deck and 2 the sides or hull of a marine vessel which in this instance is provided under the overhanging portion of its stern with a suitable bladed propeller 3. Secured to the outside of this hull is a suitably shaped plate 4 that is separated away from the same a slight distance by small spacing-blocks 5 in order to provide a suitable air-space or duct 6 between said plate and the hull of the vessel. This plate 4 preferably corresponds in shape and outline to the portion of the hull that it surrounds, that is, from a slight distance above the water line to the keel, and from the prow to between two-thirds and three-fourths of the length of the vessel. Superimposed upon this first

mentioned plate and preferably terminating at about amidship is another correspondingly shaped plate 7 that is separated therefrom by spacing-blocks 10 to form an air-space between the two plates. These plates 60 conform in general shape to each other, and at their forward ends rise above the horizontal plane of the top edge of said plates and extend up to the gunwales of the vessel to form breast-plates 8, as it were, across 65 the bow thereof. These breast-plates are each provided with a plurality of ports 9 for the ingress of air. The upper edges of these plates are preferably calked or else bent at an angle, substantially as shown, to 70 prevent the air contained between the same from escaping above the line and also prevent the accidental inlet of water.

In operation, when the boat has been started the pressure of the air that forces 75 itself through the ports 9 and the suction of the water through which the vessel travels siphons the air from between the plates 4 and 7 and the hull and distributes it under the hull, thereby permitting the bulk of the 80 boat to rest upon these escaping bubbles of air that rapidly rise around the sides thereof, but which become dissipated in the water before they reach the rudder or the propeller. These air bubbles present less 85 friction to the hull of the vessel than is the case when the boat is traveling in the solid water, and, owing to the speed at which the vessel is traveling and the lightness of the air bubbles the same will leave the rear ends 90 of the plates and travel in a path that is rearward and upward around the sides of the hull so the greater majority of said bubbles will come to the surface of the water before reaching the propelling and steering 95 apparatus.

What I claim as new is:—

1. A marine vessel having a series of shells forming air-spaces constructed one within the other on the outside of its hull and extending from its bow rearwardly to a point amidship.

2. A marine vessel comprising a hull the forward portion of which is provided with a series of shells forming air-spaces one 100 within the other upon its exterior below the water-line.

3. A marine vessel having a series of shells forming air-spaces constructed one within the other on the outside of its hull and ex- 110

- 22
- tending from its bow rearwardly to a point amidship below the water-line.
4. A marine vessel comprising a hull having a series of shells one within the other incasing its forward portion, said shells separated from each other and from said hull to form a series of enveloping air-spaces from which air is discharged rearwardly under the hull.
- 10 5. A marine vessel comprising a hull having a series of shells one within the other incasing its forward portion, said shells separated from each other and from said hull to form a series of enveloping air-spaces from which air is discharged rearwardly under the hull, and said shells having air-inlet ports in their bows above the water-line.
- 15 6. A marine vessel comprising a hull having a series of shells one within the other incasing the forward portion thereof below the water-line, said shells separated from each other and from said hull to form a series of enveloping air-spaces from which air is discharged rearwardly under the hull, and said shells having air-inlet-ports in their bows above the water-line.
- 20 7. A marine vessel comprising a hull the forward portion of which is provided with a series of air-spaces one within the other upon its exterior the inner one of which is longer than the outer.
- 25 8. A marine vessel having a series of air-spaces constructed one within the other on the outside of the hull and extending from the bow rearwardly to a point amidship the inner one of said shells being longer than the outer.
- 30 9. A marine vessel comprising a hull the forward portion of which is provided with a series of air-spaces one within the other upon its exterior below the water-line, the inner one of said shells being longer than the outer.
- 35 45. 10. A marine vessel having a series of air-spaces constructed one within the other on the outside of the hull that extend from the bow rearwardly to a point amidship below the water-line, the inner one of said shells being longer than the outer.
- 40 50. 11. A marine vessel comprising a hull having a series of shells one within the other incasing the forward portion thereof the inner one of said shells being longer than the outer, said shells separated from each other and from said hull to form a series of air-spaces from which air is discharged rearwardly under the hull.
- 45 60. 12. A marine vessel comprising a hull having a series of shells one within the other incasing the forward portion thereof the inner one of said shells being longer than the outer, said shells being separated from each other and from said hull to form a series of air-spaces from which air is dis-
- charged rearwardly under the hull, and said shells having air inlet-ports in their bows above the water-line.
13. A marine vessel comprising a hull having a series of shells one within the other incasing the forward portion thereof below the water-line the inner one of said shells being longer than the outer, said shells separated from each other and from said hull to form a series of air-spaces from which air is discharged rearwardly under the hull, and said shells having air-inlet ports in their bows above the water-line.
14. A marine vessel comprising a hull having a series of shells one within the other incasing the forward portion of said hull below the water-line, the bow portions of said shells being increased in height to extend above the water-line, and said shells being spaced away from each other and from said hull to form air-spaces from which air is discharged rearwardly therefrom under the hull.
15. A marine vessel comprising a hull having a series of shells one within the other incasing the forward portion of said hull below the water-line the inner shell being longer than the outer, the bow portions of said shells being increased in height to extend above the water-line, and said shells being spaced away from each other and from said hull to form an air-space from which air is discharged rearwardly therefrom under the hull.
16. A marine vessel comprising a hull having a series of shells one within the other incasing the forward portion of said hull below the water-line, the bow portions of said shells being increased in height to extend above the water line and are provided with air inlet ports, and said shells being spaced away from each other and from said hull to form air-spaces from which air is discharged rearwardly therefrom under the hull.
17. A marine vessel comprising a hull having a series of shells one within the other incasing the forward portion of said hull below the water-line, the inner shell being longer than the outer, the bow portions of said shells being increased in height to extend above the water line and are provided with air inlet-ports, and said shells spaced away from each other and from said hull to form air-spaces from which air is discharged rearwardly therefrom under the hull.
- In testimony whereof I have hereunto set my hand and seal this 23d day of November, A. D., 1907.
